UNITED STATES PATENT OFFICE.

NUMON N. HORTON, OF KANSAS CITY, MISSOURI.

HEATING, COOLING, AND VENTILATING APPARATUS.

SPECIFICATION forming part of Letters Patent No. 245,380, dated August 9, 1881.

Application filed February 15, 1881. (No model.)

To all whom it may concern:

Be it known that I, NUMON N. HORTON, doctor of medicine, a citizen of the United States, residing at Kansas City, in the county 5 of Jackson and State of Missouri, have invented Improvements in Heating, Cooling, and Ventilating Apparatus, of which the following is a specification.

My invention relates particularly to certain 10 improvements for the adaptation to the ventilation and heating and cooling of railway-cars of a system of ventilation and heating or cooling which I have described in another application.

15 My present improvements relate, first, to a mode of connecting my system of heating or cooling and ventilating pipes with a locomotive-engine boiler for the purpose of applying the invention to railway-cars; second, to an 20 improved arrangement of devices for delivering the heated air and discharging vitiated air; and, third, to a coupling for the hose by which the air is conducted from car to car.

In order that the invention may be fully understood, I will proceed to describe it with reference to the accompanying drawings.

Figure 1 is a vertical longitudinal section of a baggage-car with my heating and ventilating apparatus applied. Fig. 2 is a longitudinal section of the heating or cooling coil and its accessories on a larger scale. Fig. 3 is a vertical longitudinal section of a passenger-car, showing the induction and discharge apparatus therein. Fig. 4 is a longitudinal section of a part of the air-pipe, showing the damper therein and the mode of locking the same. Fig. 5 is a vertical section of the exhaust or discharge pipe and the nozzle therein on a larger scale. Fig. 6 is a perspective view 40 of parts of the hose-coupling detached. Fig. 7 is a side elevation of one of the coupling-heads. Fig. 8 is a longitudinal section of the two heads connected.

In Fig. 1 I have shown within the baggage-car, at B, a boiler, and at E an engine for working the fan F for producing a forced current of air after the manner described in my other application, hereinbefore referred to, for a system of heating and ventilating applicable to 50 buildings as well as to railway-cars.

A represents a drum or casing containing

the heating or cooling coil C, which, for heating purposes, is supplied with steam either directly from the boiler B or from the exhaust of the engine, as shown; or it may, in the application of my invention to car-heating, be connected by a pipe, e', with the locomotive-boiler through a suitable hose and coupling, and by connecting the said steam-pipe with the engine E, as shown, the boiler B in the baggage-car may be entirely dispensed with.

The steam-coil C may either deliver the steam into the air through a pipe, e, as shown, or the circulation of steam therein may be so regulated as to return the entire water of condensation into the boiler through a suitable pipe.

F represents a fan, which is driven by the engine E by means of belts and pulleys or other equivalent appliances, and is employed for forcing air through the pipe G and branches 70 G' G'', the first passing into the casing or drum A, and the second around the same.

For cooling the air in hot weather cold water, either iced or not, is passed through the coil C.

Both the drum A and the lateral passage G² are connected to a common conducting tube or trunk, G³, by which the air, either heated or not, as desired, is conducted and delivered to hose H H', connected by the coupling I, 80 so as to be passed from car to car throughout the entire length of the train. V represents a two-way valve controlling the bifurcated or branched passages from the air-pipe G to the drum A and the lateral pipe or passage G², so that the entire body of air may be passed through the drum A in contact with the heating or cooling coil C or through the lateral passage G² around the drum, so as to avoid being heated or cooled, or any relative 90 proportions of the air being passed through the respective channels. The entire body of air delivered or conducted through the pipe or trunk G³ may be heated or cooled to the required degree.

The degree of heat is nicely regulated by the graduation of the respective passages by means of the valve, as aforesaid, the hinged rod J, by which the valve is moved, being notched, as shown, and pressed forward by a spring, K, 100 fixed to the outside of the pipe. The particular notch in which the rod is held indicates

the precise position of the valve with respect to the passages which it controls. The ventilating-trunks L, within the passenger-cars, take the air from the hose H at one end and 5 deliver it to a similar hose, H, at the other end of the car, each hose being provided with a similar coupling, I, adapted for interchangeable connection, so that the cars may be connected in customary manner either end to, or 10 either end of any passenger-car may be connected with the hose H of the baggage-car in which the air forcing and heating apparatus is contained.

To adapt the couplings to come together interchangeably, they are each made with a semi-circular flange, p, to slip within the opposite head, as illustrated in Fig. 8, and each head has on one side a spring-catch, q, and on the other a hole, r, to receive the spring-catch of the 20 other head. With the air-trunks L, within the cars, are connected vertical air-pipes M, leading down the sides of the car, between the windows adjacent to the seats, and delivering air under control of registers N, which are accessible to the passengers.

In order to carry off vitiated air from the cars and facilitate the delivery of fresh air within the same, either heated or not, as the temperature of the atmosphere may require, I employ 25 discharge-pipes O, opening near the floor of the car, so as to take the cooler and more vitiated stratum of air, and having within them upturned nozzles P, connected by small pipes Q with the air-forcing pipes or trunks L, so as to 30 cause an active induced current of air. The discharge-pipes O are located, two in a car, at opposite diagonal corners, in the places commonly occupied by heating-stoves.

It is manifestly unimportant whether the 40 air-forcing fan F be located, as already described, so as to drive the air through drum A

or lateral pipe G², or both, or whether it be located within the trunk G³, with which the said drum A and pipe G² both communicate, so as to cause an exhaust-current through said drum 45 A or lateral pipe G², or both. I have accordingly shown at F' a fan which will act by exhaust, as aforesaid; but it will be clearly understood that the force-fan F and the exhaust-fan F' will not both be required, but either 50 55 may be used, as preferred.

It is also manifest that any suitable form of rotary or reciprocating blower or air-pump may be used in lieu of common centrifugal fans indicated.

A damper is shown at T, in the air-trunk L at each end of the car, for the purpose of closing said trunk at the rear end of a train. The shaft of said damper is provided with a cross-bar or handle, U, for turning it, and with a 60 square head, W, for the engagement of a pivoted forked catch, X, so as to hold the damper securely in either open or closed position.

Having thus described my invention, the following is what I claim as new therein and 65 desire to secure by Letters Patent:

1. The combination, in a railway-car, of a suitable air-forcing appliance, F, an engine, E, for working the same, branched pipes G G' G² G³, heater or cooler A C, and a pipe, e', for 70 supplying steam from the locomotive to the engine E and heating-coil C, as explained.

2. The combination, in a railway-car, of hot-air trunks or conductors L, delivery-pipes M, and forced-exhaust apparatus consisting of 75 the discharge-pipe O, opening near the floor, and the upturned nozzle P contained therein, substantially as and for the purpose set forth.

NUMON N. HORTON.
